ANTENNA FEED SYSTEM

Nathaniel I. Korman, Camden, N.J., assignor to Radio Corporation of America, a corporation of Delaware

Filed Sept. 30, 1947, Ser. No. 776,927

11 Claims. (Cl. 343—756)

This invention relates to antenna feed systems, and particularly to improvements in lobe switching antenna systems. A lobe switching antenna is a directive radiator or collector having a single-lobe pattern; lobe switching consists in changing the direction of the lobe with reference to a physical axis of the antenna. Lobe switching ordinarily is cyclical, and may be made along one coordinate, for example alternately left and right, or may comprise a cycle of four positions such as up, left, down and right.

The principal object of this invention is to provide methods and means for lobe switching which involve no moving parts and enable maximum effective utilization of the effective aperture of the directive radiator structure.

Another object is to provide feed networks for simultaneous lobing of a directive radiator, i.e. to separate the components of a received signal in accordance with the deviation of the direction of arrival of said signal from a reference line.

The invention will be described with reference to the accompanying drawings, wherein:

Figure 1 is a schematic diagram in elevation of a directive structure of one type which may be used with the present invention.

Figure 2 is a group of graphs representing typical directive patterns which can be produced with the device of Fig. 1.

Figure 3 is a group of schematic diagrams illustrating types of feed cavity excitation required to produce the respective patterns shown in Fig. 2.

Figure 4 is a further group of graphs showing directive patterns obtainable by simultaneous excitation of the feed cavity in two of the modes shown in Fig. 3.

Figure 5 is a perspective diagram of a complete feed system embodying the instant invention.

Figure 6 is a sectional view of one of the elements of Fig. 5.

Figure 7 is a sectional elevation of another of the elements of Fig. 5, and

Figure 8 is a perspective view of a wave guide junction used in the system of Fig. 5.

Similar reference characters are applied to similar elements throughout the drawings.

Referring to Fig. 1, a type of directive structure, commonly used for the relatively short waves (1 to 10 cm.) associated with microwave radar, comprises a parabolic reflector 1 and a radiator source 3 at the focal point of the reflector. The effective area or opening of the reflector is known as its aperture and it is the aperture which determines how sharp the directive beam or lobe can be made. The larger the aperture in relation to a wavelength, the sharper is the beam.

To achieve the maximum effectiveness of the reflector, the source 3 must be directive so as to "illuminate" or substantially cover the reflector with radiation. If the beam from the source is too sharp, only a part of the reflector is utilized; if it is too broad, some of the energy

misses the reflector and is wasted. The source 3 may be an open ended wave guide or cavity, with its open end facing the reflector. The optimum size of the opening is fixed by the diameter and focal length of the reflector.

Figure 2A is a graph of field strength at different angles of azimuth or elevation across the mouth of the source 3. It is a maximum at the center, decreasing to zero toward the extremes. This represents a single radiation lobe directly along the central axis of the reflector 1 and the cavity 3, and provides a beam from the reflector 1 as indicated by the lines 5 in Fig. 1. Referring to Fig. 3A, the cavity 3 is seen to be of square cross section. To provide the radiation pattern shown in Fig. 2A, the cavity 3 is excited by a field whose electric vectors extend vertically across the cavity.

Figure 2B shows a radiation pattern comprising two lobes extending to the left and right respectively of the reference axis. The showing of the right hand lobe below the abscissa in Fig. 2B is to indicate that the energy in this lobe is 180 degrees out of phase with that in the left hand lobe. The excitation required in the cavity 3 to produce the pattern of Fig. 2B is shown in Fig. 3B. This mode is that known in the wave guide art as the TE_{02} , and that shown in Fig. 3A is the TE_{01} mode. Either of the patterns shown in Figs. 2A and 2B may be reversed in phase by reversing the excitations shown in Figs. 3A and 3B.

The excitation shown in Fig. 3C requires the presence of a horizontal conductive septum 7 across the cavity 3. This part, although not shown in Figs. 3A and 3B, does not have any effect on the TE_{01} and TE_{02} modes of those figures. The corresponding radiation pattern, shown in Fig. 2C, has the same characteristics in elevation as that of Fig. 2B has in azimuth.

The directive pattern illustrated by Fig. 4A results from the simultaneous presence of the excitation patterns of Figs. 3A and 3C, and is the sum of the radiation patterns of Figs. 2A and 2C. The directive pattern of Fig. 4B is obtained by reversing the phase of either of its two components, for example that of Fig. 3C. Similarly, Fig. 4C shows the result of combined excitation in the modes of Figs. 3A and 3B, and Fig. 4D represents the effect of reversing one of the components for example that of Fig. 3B.

The foregoing description is based on the assumption that the feed cavity 3 is energized by a generator, and is used for transmission of signals. However, received energy striking the reflector will also be applied to the cavity and will set up excitation patterns like those of Figs. 3A, 3B and 3C, or combinations thereof, depending upon the direction of arrival of the incident waves. Thus energy may be transmitted or received directly in a lobe extending straight along the axis of the reflector 1, or in a lobe which deviates either laterally or vertically from the axis, by coupling the cavity 3 to a utilization device (transmitter or receiver) in such manner as to produce or respond to the proper mode or combination of two of the modes shown in Figs. 3A, 3B and 3C.

The dimensions of the mouth of the cavity 3 must of necessity be a compromise between the most effective aperture for excitation like that of Fig. 3A and the best for excitation like that of Fig. 3C. Preferably the design is such that little or none of the radiated energy misses the reflector 1 when the beam lobe is off-axis. This implies that not all of the reflector area is effective simultaneously. However, the use of a single feed cavity as described enables a closer approach to ideal illumination of the reflector than can be obtained by means of separate individually excited cavities, since it affords maximum utilization of the space in the vicinity of the focal point.

Figure 5 shows a network of wave guides connected to the cavity 3 to provide the various types of excitation and response which have been described. The system of Fig. 5 is arranged to perform the following functions:

(a) Transmit pulses from a relatively high power transmitter in a single lobe directly along the reference axis, i.e. the axis of the reflector.

(b) Receive pulses such as energy reflected from objects lying within the solid angle subtended by the transmitted beam, and apply the received energy to a "sense" or reference phase receiver.

(c) Divide the received signals of (b) above, between an up-down receiver and a left-right receiver, in accordance with the elevation and azimuth respectively of the line of arrival of the received signals. This is known as "simultaneous" or "monopulse" lobing.

(d) Transmit pulses from a relatively low power transmitter selectively and/or cyclically in directive lobes above, below, to the left and to the right of the reference axis.

It will be apparent that some of the above functions may be omitted if desired.

The structure of Fig. 5 includes four wave guides 7, 9, 11 and 13 respectively terminating in the top, bottom and sides of the cavity 3. The wave guides, and all others shown in Fig. 5 are rectangular and operate with the electric field vectors across the narrow dimension. The wave guides 7 and 9 come together at a junction 15 with two other wave guides 17 and 19. The junction 15 is of the type known in the wave guide art as a "hybrid T" or "side outlet T," and is shown more clearly in Fig. 8.

Referring to Fig. 8, the hybrid T comprises wave guides 21 and 23 joined and in alignment with each other, a wave guide 25 lying in the same plane (i.e. with its wide dimension parallel to that of guides 21 and 23) and joining the guides 21 and 23 at a right angle thereto, and a fourth wave guide 27 perpendicular to all of the wave guides 21, 23 and 25 but with its wide dimension parallel to those of the guides 21 and 23.

The characteristics of the hybrid T, assuming the various arms to be matched, are as follows:

Energy travelling down the arm 27 divides equally at the junction, one half flowing out the arm 21 and one half flowing out the arm 23, none flowing out the arm 25. If the electric vector of the applied energy is in the direction of the arrow 29, the vector in the arm 21 is up, and that in the arm 23 is down. Stated another way and somewhat more accurately the voltage at any point in the wave guide 23 is 180 degrees out of phase with that at the corresponding point in the guide 21.

Energy travelling toward the junction on the arm 25 is divided equally between the arms 21 and 23, none going up the arm 27. If the electric vector in the arm 25 is up, as shown by the broken arrow 31, the vectors in the arms 21 and 23 are also up. In other words, the arms 21 and 23 are excited in phase with each other by energy entering from the arm 25. Conversely if energy flows in both arms 21 and 23 equally toward the junction, it will all go up the arm 27 if corresponding points in the arms 21 and 23 are 180 degrees out of phase, and it will all go out the arm 25 if the arms 21 and 23 are in phase. As long as the impedances are matched, no energy can flow between the arms 25 and 27.

Returning to Fig. 5, the wave guides 11 and 13 join at a hybrid T 33 with wave guides 35 and 37. The guides 35 and 19 join at a hybrid T 39 with a main wave guide 41 and a guide section 43 which terminates in a matched load, not shown. The main wave guide 41 extends directly to the high power transmitter, not shown, which is to provide radiation along the reflector axis. Branching from the main wave guide 41 near its lower end is a wave guide 45 which extends to the sense receiver, not shown. The guide 45 includes a protective gap 47, shown more clearly in Fig. 6. A short branch 49 also connects to the main guide near the guide 45, and contains a gap 51.

Referring to Fig. 6, the receiver protective circuit, called a T-R switch in the radar art, comprises the gap 47 across the wave guide 45, at a distance from its junction with the main guide 41 such that when the gap 47 is ionized, it prevents the transfer of energy into the guide 45 from the main guide 41 and to the receiver. To prevent received energy from being absorbed by the transmitter, the wave guide section 49 and the gap 51 are arranged so that when the gap 51 is open (not ionized) energy travelling up the wave guide 41 from the antenna is reflected back down to go out the wave guide 45. Thus the antenna is effectively connected to the transmitter when the gaps are ionized and to the receiver when the gaps are not ionized. Ionization of both gaps is caused by each pulse of energy from the transmitter but received energy is ordinarily too feeble to ionize either gap. The gap 51 is generally referred to as the anti-T-R or ATR gap.

The wave guide 17 (Fig. 5) branches to a wave guide 53 going to the up-down receiver, not shown. T-R and anti-T-R gaps are provided at the branch connection, and the guide 17 continues to a junction 55, where it branches into two wave guides 57 and 59. The wave guide 37 likewise connects to a branch line 61 which goes to the left-right receiver, not shown, and to parallel branches 63 and 65. The branches 63 and 65 join the branches 57 and 59 respectively, and their junctions are coupled to the main wave guide 41.

The branch wave guides 57, 59, 63, and 65 include switching tubes or gaps 71, 73, 75 and 77 respectively. One of these devices is shown in detail in Fig. 7. It includes a gap formed by electrodes 79 and 81 on the upper and lower surfaces of the wave guide. The electrode 79 is hollow, and a control or starting electrode 83 is supported within the electrode 79 by a glass seal 85. The gap is designed so that the maximum voltage induced across it by the low power transmitter is not enough to cause ionization, but pulses from the high power transmitter will break down the gap. However, ionization is normally maintained by application of a high D.-C. voltage between the electrode 83 and the body of the wave guide.

The positions of the switching gaps in the branches 57, 59, 63, and 65 are selected so that when the respective gaps are ionized, no energy can flow into the branches from the main guide 41. Upon removal of the D.-C. voltage from any switching gap, the corresponding branch guide is effectively connected to the main wave guide. The connections of the branch guides 57, 59, 63, and 65 to the main guide 41 are somewhat like a hybrid T, in that the branches 57 and 63 are energized out of phase with the branches 59 and 65. However, only part of the energy goes into the particular branch whose switching gap is open; the other part goes on down the wave guide 41.

A wave guide 67 branches off near the upper end of the main wave guide 41 to the low power transmitter, not shown. The guide 67 includes a T-R gap 69. This gap, and the associated ATR gap, are both designed to break down or ionize only upon application of relatively high power to the guide 41. The rest of the TR and ATR gaps in the system are designed to break down at the relatively low power level as supplied to the wave guide 67.

The operation of the system of Fig. 5 is as follows: High power pulses supplied to the upper end of the wave guide 41 break down all of the TR, ATR and switching gaps in the network. Substantially all the energy flows directly down the main wave guide 41 to the hybrid T 39 where it divides into equal parts going to the hybrid T's 15 and 33 respectively. The energy reaching these junctions is again divided into equal parts, feeding the cavity 3 through the four wave guides 7, 9, 13 and 11. This produces the type of excitation shown in Fig. 3A,

which gives the directive pattern represented in Fig. 2A, comprising a lobe coaxial with the reflector 1.

Return signals reflected for example by a target lying on the axis of the reflector 1, induce a field in the cavity 3 in the configuration of Fig. 3A. This energizes the four wave guides 7, 9, 11 and 13 equally. The guides 11 and 13 are supplied in phase with each other, and the guides 7 and 9 in phase opposition with each other. Accordingly, all the energy reaching the hybrid T 15 along the guides 7 and 9 goes out the guide 19. Owing to the different arrangement of the hybrid T 33, the in-phase energy supplied to it by the guides 11 and 13 all goes out the guide 35. At the hybrid T 39, the energy arriving on the guides 19 and 35 combines in phase and goes up the main wave guide 41. It is reflected by the stub 49, whose ATR tube is open at this time, and goes out the guide 45 to the sense receiver.

Return signals which do not arrive along the axis, such as those reflected by an off center target, will induce fields in the cavity 3 like those shown in Fig. 3B or 3C, or a combination thereof if the target is off both in azimuth and in elevation. Suppose the configuration to be that of Fig. 3C. No energy is accepted by the guides 11 and 13 because they cannot propagate this mode. The guides 7 and 9 are excited in phase with each other, and equally. At the hybrid T 15, the incoming energy combines in phase and all of it goes out the wave guide 17. The ATR gap near the junction with the wave guide 53 prevents any flow further up the guide 17, so all of the energy goes out the guide 53 to the up-down receiver. The phase of the energy at this point will reverse if the field in the cavity 3 is reversed in phase. The intensity of the field in the cavity, and hence the voltage appearing on the guide 53, depends on the angular deviation of the return signal from the reference axis.

Suppose now that the field induced in the cavity 3 by the return signal is of the form shown in Fig. 3B. In this case the wave guides 7 and 9 accept no energy, and the guides 11 and 13 are energized out of phase, causing flow up the arm 37 of the hybrid T 33. Substantially all of the energy goes to the wave guide 61 leading to the left right receiver. By means which are not a part of the present invention and hence will not be described or claimed, the outputs of receivers connected to the wave guides 45, 53, and 61 are combined to provide control signals for indicating target deviation and/or correcting such deviation.

Relatively low power pulses are applied to the wave guide 67. These are to be radiated selectively in directive beams above, below, to the left and to the right of the axis. The power is insufficient to close the gap 69 or the ATR gap associated with it, and cannot close any of the switching gaps 71, 73, 75, or 77. However all of the latter except one are held closed by application of a high D.-C. voltage from a control source, not shown. Which one is left open depends upon which of the four available directive patterns is being selected. Assume for example that the gap 75 is open. Energy applied to the wave guide 67 is barred by the associated ATR gap (un-ionized) and must go down the guide 41. At the junction with the guides 57, 59, 63 and 65 it divides, part going into the open guide 63 and the remainder continuing down the main guide 41. The TR gap 47 and ATR gap 51 both close, barring the wave guide 45 and allowing the energy to flow to the hybrid T 39. Here it divides equally between the guides 19 and 35, is again divided at the hybrid T's 15 and 33, and provides a field like Fig. 3A in the cavity 3.

The other part of the supplied energy goes down the guide 37, past the barred junction with the guide 61, to the hybrid T 33. Here it divides equally, exciting the guides 11 and 13 equally but in opposite phases. This induces a field like Fig. 3B in the cavity 3. The combination of the fields of Figs. 3A and 3B provides a

directive lobe like that of Fig. 4C or 4D, to the left or to the right of the axis, depending upon the phase relationship between the energy travelling directly down the guide 41 and that in the guide 63. Assume it to be that of Fig. 4C. Then the pattern of 4D can be obtained by closing the guide 63 and opening the guide 65, thus reversing the phase of the energization of the guide 37.

The wave guide 17 can be energized by opening either of the switching gaps 71 and 73. This provides a field 10 in the cavity 3 of the form shown in Fig. 3C. Combined with the field of Fig. 3A, the field provided by opening the gap 71 will result in the directive pattern shown in Fig. 4A. The phase of the component corresponding to Fig. 3C may be reversed by opening the gap 15 73 instead of the gap 71, producing the directive pattern of Fig. 4B.

From an examination of Fig. 3 it will be apparent that the mode of excitation illustrated by Fig. 3A is one of even symmetry with respect to the vertical plane 20 through the wave guide axis and also having even symmetry with respect to the horizontal plane through the wave guide axis. Referring to Fig. 3B, it is clear that the mode of excitation therein illustrated is one of odd symmetry with respect to a vertical plane through the wave guide axis, although possessing even symmetry with respect to the horizontal plane. Conversely, the mode illustrated in Fig. 3C has odd symmetry with respect to the horizontal plane and even symmetry with respect to the vertical plane. It will be clear that the phasal relationship of energy in wave guide 45 say (being coupled solely to the energy in the wave guide mouth of mode illustrated in Fig. 3C), will provide a determination of the sense of the radiation pattern of the transmitted or received energy in waveguide 3 with respect to the horizontal plane of odd symmetry. A similar relationship obviously exists between the phasal relationship of energy in wave guide 61 with respect to the energy in the mode of Fig. 3A and that in the mode of Fig. 3B to give a sensing relationship with regard to the vertical plane. 40 The phasal relationship in the sensing wave guides 45 or 61 may be related to the transmitted or received energy in wave guide 41 or to the energy in the principal mode illustrated in Fig. 3A.

When referring to the horizontal plane of symmetry or the vertical plane of symmetry in the foregoing, applicant refers, of course, to the central plane through the waveguide mouth. Thus, for example, the plane 7 in Figure 3C is the horizontal plane of symmetry. With reference to the even and odd symmetry, the definition of these as classically established will be recalled. In a system of mutually perpendicular axes X, Y and Z along which are measured variables x, y and z, the definition is, as appears in numerous standard mathematical texts, the function $f(x,y,z)$ is even with respect to the Y-Z plane if $f(x,y,z)$ equals $f(-x,y,z)$ and the function is odd if $f(x,y,z)$ is equal to $-f(-x,y,z)$. Accordingly, referring to Figure 3C and the plane 7, it is clear that the mode there illustrated has odd symmetry because the value of the vectors an equal distance normally above and below any chosen point in the plane is the same in magnitude but reversed or negative in direction.

The invention has been described as an improved feed system for high frequency antennas of the type comprising a radiation source and a director device such as a reflector. Lobe switching and similar effects are achieved with maximum utilization of the director aperture and without moving parts, by making the radiator in the form of a single cavity with plural excitation means, and energizing said excitation means to induce fields of various modes which provide the required directive patterns.

I claim as my invention:

1. In a simultaneous lobing antenna system including a radiation focussing device, a radiator substantially at the focal point of said device, said radiator comprising a

cavity device of substantially square cross section open at the front and closed at the back, two wave guides each entering one side of said cavity device respectively, and two further wave guides entering the top and bottom respectively of said cavity device; a common wave guide, and a hybrid T connecting both of said first mentioned wave guides in phase opposition with each other to said common wave guide, a second common wave guide and a hybrid T connecting both of said second mentioned wave guides in phase opposition with each other to said second common wave guide; a main wave guide, and means connecting said main wave guide to both of said hybrid T's to connect said first mentioned two wave guides cophasally to said main wave guide and said second mentioned two wave guides cophasally with each other to said main wave guide; four branch wave guides, two connected in parallel to each of said common wave guides, means connecting each of said branch wave guides cophasally with a branch wave guide from the other of said common wave guides to said main wave guide, and switching means included in each of said branch guides to render it selectively effective and ineffective to transmit energy.

2. A lobe switching antenna system including a wave focussing device, a single radiator fixed with respect to said focussing device at the focal point thereof, said radiator comprising a cavity device in the form of a rectangular parallelepiped and including a substantially square opening facing said focussing device, four wave guides entering said cavity device respectively at the four surfaces adjacent the open side thereof, a main wave guide, and means interconnecting said four wave guides in pairs selectively in phase agreement and in phase opposition to said main wave guide.

3. A lobe switching antenna system including a wave focussing device, a radiator fixed with respect to said focussing device, said radiator comprising a cavity device including an opening facing said focussing device, four wave guides entering said cavity device respectively at the four surfaces adjacent the open side thereof, a main wave guide, and means interconnecting said four wave guides in pairs selectively in phase agreement and in phase opposition to said main wave guide.

4. A feed system for directional antennas, comprising a cavity device having an opening of substantially square cross section, four orthogonally related wave conduit means entering said cavity device in directions respectively perpendicular to the sides of said opening and terminating within said cavity device, a main wave conduit, and means connecting said first mentioned conduits in pairs selectively in phase agreement and in phase opposition to said main conduit.

5. In a simultaneous lobing antenna system including a radiation focussing device, a radiator substantially at the focal point of said device, said radiator comprising a cavity device of substantially square cross section open at the front and closed at the back, two wave guides each entering one side of said cavity device respectively, and two further wave guides entering the top and bottom respectively of said cavity device; a common wave guide, and a hybrid T connecting both of said first mentioned wave guides in phase opposition with each other to said common wave guide, a second common wave guide and a hybrid T connecting both of said second mentioned wave guides in phase opposition with each other to said second common wave guide; a main wave guide, and means connecting said main wave guide to both of said hybrid T's to connect said first mentioned two wave guides cophasally to said main wave guide and said second mentioned two wave guides cophasally with each other to said main wave guide.

6. In a lobe switching antenna system including a radiation focussing device, a radiator substantially at the focal point of said device, said radiator comprising a cavity

device of substantially square cross section open at the front and closed at the back, two wave guides each entering one side of said cavity device respectively, and two further wave guides entering the top and bottom respectively of said cavity device; a common wave guide, and means connecting both of said first mentioned wave guides in phase opposition with each other to said common wave guide, a second common wave guide and means connecting both of said second mentioned wave guides in phase opposition with each other to said second common wave guide; a main wave guide, and means connecting said main wave guide to said first mentioned two wave guides and to said second mentioned two wave guides cophasally.

15 7. In a lobe switching antenna including a radiation focussing device, a radiator substantially at the focal point of said device, said radiator comprising a cavity device of substantially square cross section open at the front and closed at the back, two wave guides each entering one side of said cavity device respectively, and two further wave guides entering the top and bottom respectively of said cavity device; a common wave guide, and means connecting both of said first mentioned wave guides in phase opposition with each other to said common wave guide, a second common wave guide and means connecting both of said second mentioned wave guides in phase opposition with each other to said second common wave guide; a main wave guide, and means connecting said main wave guide to said first mentioned two wave guides and to said second mentioned two wave guides cophasally, four branch wave guides, two connected in parallel to each of said common wave guides, means connecting each of said branch wave guides cophasally with a branch wave guide from the other of said common wave guides to said main wave guide, and switching means included in each of said branch guides to render it selectively effective and ineffective to transmit energy.

8. In a simultaneous lobing antenna system, a wave guide having an open mouth portion for radiation or reception of electromagnetic energy, said portion having a longitudinal axis and having transverse dimensions to propagate at an operating frequency a first mode having odd symmetry with respect to a plane passing through said axis and to propagate energy at said frequency in a second mode having even symmetry with respect to said plane, means to excite said wave guide portion in said first mode at said frequency, and means to excite said wave guide portion simultaneously with the excitation of said first mode selectively cophasally and antiphasally in said second mode at said frequency, thereby to direct radiation on one side or the other of said plane in accordance with the cophasal and antiphasal relationship between said modes.

55 9. The combination claimed in claim 8, said means to excite said first mode including a transducer coupled to said wave guide portion to energize and to be energized solely by energy in said first mode, whereby the phasal relationship to energy coupled to said transducer means is dependent upon the cophasal and antiphasal relationship between said modes to provide a sensing in accordance with the direction of radiated or received energy on one side and the other of said plane.

10. In a simultaneous lobing antenna system, a wave guide having an open mouth portion for radiation or reception of electromagnetic energy, said portion having a longitudinal axis and having transverse dimensions to propagate energy at an operating frequency in first and second modes of odd symmetry respectively with respect to first and second planes normal to each other and passing through said axis and to propagate at said frequency a third mode symmetrical with respect to both said planes, means to excite said wave guide portion in said third mode at said frequency, and means to excite said wave guide portion simultaneously with the excitation

of said third mode in at least one of said first two modes selectively cophasally and antiphasally at said frequency whereby the radiation or reception pattern of said open mouth wave guide portion is lobed at an angle with respect to said axis.

11. In a simultaneous lobing antenna system, the combination of a wave guide having an open mouth portion for radiation or reception of electromagnetic energy, said portion having a longitudinal axis and having transverse dimensions to propagate energy at an operating frequency in first and second modes having odd symmetry respectively with respect to first and second planes normal to each other and passing through said axis and to propagate energy at said frequency in a third mode having even symmetry with respect to both said planes, means to excite said wave guide portion in said third mode at said frequency, and means to excite said wave guide portion simultaneously with the excitation of said third mode in at least one of said first two modes at said frequency selectively cophasally and antiphasally with respect to said third mode, said last named means including two transducers coupled to said wave guide portion, one coupled solely to energize and to be energized by energy in

5 said wave guide portion in said first mode, and the other coupled solely to energize and to be energized by energy in said wave guide portion in said second mode, each in a phasal relationship dependent on the phase of its coupled mode with respect to energy in said third mode, whereby said transducers each provide sensing means in accordance with the phase of its energy corresponding to the position of the lobe pattern of said wave guide portion on one side or the other of the plane of odd 10 symmetry of its coupled mode.
